UNITED STATES PATENT OFFICE.

HUBERT LANG, OF CHICAGO, ILLINOIS, ASSIGNOR TO THE GOSS PRINTING PRESS COMPANY, OF CHICAGO, ILLINOIS, A CORPORATION OF ILLINOIS

ROTARY FOLDING MECHANISM.

No. 899,743.

Specification of Letters Patent.

Patented Sept. 29, 1908.

Application filed May 9, 1908. Serial No. 431,782.

To all whom it may concern:

Be it known that I, HUBERT LANG, a citizen of the United States, residing at Chicago, in the county of Cook, State of Illinois, have invented certain new and useful Improvements in Rotary Folding Mechanism, of which the following is a specification, reference being had to the accompanying drawings.

10 My invention relates to folding mechanism for rotary presses wherein the folding blade carried by a rotary carrier is operated by suitable mechanism, which, by moving the folding blade into and out of folding position while traveling in the same general direction therewith, operates the folding blade without a blow or violent contact of parts.

20 My invention particularly relates to improvements in the folding mechanism shown and described in Letters Patent to Hans P. Husby, granted November 12, 1907, No. 871,038.

25 More particularly still, my invention relates to improvements in rotary folding mechanism in which the folding blade on the rotary carrier is provided with a recessed or slotted cross head at its end and is operated so as to move the folding blade into and out 30 of folding position by a rotary member provided with a stud adapted to engage the slotted or recessed cross head. Such recessed cross head operated by rotary members is shown and described in patent to 35 Hans P. Husby, granted November 12, 1907, No. 870,964. In this patent, however, two rotary members are shown which successively engage a slotted cross head, one upon each end of the folding blade shaft, the one 40 rotary member moving the folding blade into folding position and the other thereupon engaging the recess in the cross head on the other end of the shaft and moving the folding blade out of folding and into normal position.

45 It is the principal object of my invention to provide a mechanism in which the folding blade, provided with a recessed cross head, may be engaged in normal position, moved into folding position, moved out of folding position, and delivered in normal position by a single rotary member provided with an engaging stud, and, generally speaking, I accomplish this object by placing the rotary member with its axis of rotation between the

axis of rotation of the rotary carrier and the line of travel of the axis of the folding blade shaft instead of having the axis of the rotary member exterior to the line of travel of the axis of the folding blade.

50 In the accompanying drawings:—Figure 1 is an end view, showing the folding blade in the act of being engaged by the rotary member and while still in normal position. Fig. 2 is an end view, showing the folding blade in 55 folding position in solid lines and in normal position just freeing itself from the engaging studs in dotted lines. Fig. 3 is a side elevation, with the folding cylinder and framework broken away. Fig. 4 is a detail, being 60 an isometric view of the rotary member which engages the slotted cross head.

65 Referring to the drawings:—5 indicates a rotary carrier which is journaled in a suitable framework, as 6, and driven in any well-known and approved manner.

70 7 indicates shafts journaled in the rotary carrier 5.

75 8 indicates folding blades which are secured in any appropriate manner to the 80 shafts 7.

85 9—9 indicate folding rollers which are journaled in suitable framework, as 6, and are driven in the usual manner.

90 10 indicates cross heads which are secured upon the ends of the shafts 7 exterior to the rotary carrier. The cross heads 10 are provided at each end with recesses 11 which are adapted to engage the studs on the rotary member hereinafter described.

95 12 indicates a gear which is secured upon the rotary carrier shaft exterior to the rotary carrier 5 and beyond the cross heads 10.

13 indicates an idler gear which is journaled upon a suitable stud axle 14 mounted 100 in the framework 6.

105 15 indicates a gear which is journaled upon a stud axle 16 mounted in the framework 6. The gears 12 and 13 register with each other, and the gears 13 and 15 with each other, and are so related to one another in their number of teeth that the gear 15 will rotate four times for each three revolutions of the gear 12 and therefore will rotate four times for every three revolutions of the rotary carrier.

110 17 indicates a disk which is secured to or formed integral with the gear 15 and upon the inner surface of said gear 15 between it and the plane of the cross heads 10.

18, 18^a and 18^b indicate studs, preferably 110

in the form of rollers, which project from the inner surface of the disk 17 so as to register with and engage the recesses in the ends of the cross heads, as hereinafter described.

5 The studs 18, 18^a and 18^b are equally distant from the center of the disk 17 and equally distant from each other. The parts move in the direction indicated by the arrows in Figs. 1 and 2. The diameter of the disk 17 10 and the location of the studs thereon is such that the circle in which said studs travel will intersect the circle in which the axis of said folding blade travels above the folding rollers at the point of engagement of said studs 15 with the cross head and at the point at which said studs disengage the said cross head.

19 indicates a circular guide supported upon suitable framework, as 20, exterior to 20 the rotary carrier 5 and in register with the plane of travel of the cross heads 10. The inner surface of the guide ring 19 is a circle concentric with the axis of rotation of the carrier and is adapted to form a guide which 25 will hold the cross heads and therefore the folding blade in normal inoperative position while traveling around with the carrier until the folding movement is made, the guide being cut away at its bottom above the folding 30 rollers 9 to permit the folding operation.

In practice the rotary carrier 5 is preferably used as one member of a transverse cutting mechanism, and is therefore provided with usual slots 21 which coöperate with a 35 knife 22 on cutting cylinder 23 to sever the paper transversely.

The operation of the above-described devices is as follows:—The parts rotating in the direction indicated by arrows in Figs. 1 and 40 2, the cross heads 10 travel around in the guide 19 holding the folding blades in normal position until one of the cross heads reaches the open space at the bottom of the guide. At this moment, with the gear 15 and therefore 45 the disk 17 rotating in the same direction as the rotary carrier, the cross head overtakes the roller 18, as shown in Fig. 1, and causes the said roller to engage the recess in the lead end of the cross head. As 50 the parts continue their rotation, by the interengagement of the stud 18 and the recess in the cross head, the cross head will be moved into the position shown in solid lines in Fig. 2,—that is to say, with the blade in 55 the vertical plane between the rollers 9—9,—thus tucking the paper between the folding rollers 9—9 and causing it to be folded. As the rotation continues, the cross head, by the interengagement of the stud 18 in the recess 60 in the said cross head, will be moved out of folding position and back into normal position, as shown in dotted lines in Fig. 2, at which point the cross head and the stud will 65 separate from one another and the stud be released from the said recess, the cross head

being thus delivered in normal position to the guide 19 to be carried around thereon. As the rotation continues, the lead end of the opposite cross head will be engaged in the same manner and operated by the stud 18^b, 70 skipping the stud 18^a. Upon the completion of the next semi revolution of the carrier, the lead end of the cross head first engaged, which will be the opposite end from that first engaged, will be engaged by the 75 roller 18^a, the roller 18 being passed over, and the folding operation again completed.

By driving the gear and therefore the disk 17 at a rate which compares with the rate of rotation of the rotary carrier as four to three, 80 and, by providing the disk 17 with three studs equally distant from each other,—that is to say, one hundred and twenty degrees apart,—I am enabled to operate the folding blade in a proper curve both on moving into 85 and on moving out of folding position, so that the paper may be properly folded, and, as has been said above, by so placing the rotary disk 17 that its axis of rotation comes between the axis of the rotary carrier and the 90 circle on which the axis of the folding blade travels, I am enabled to operate the slotted cross head both into and out of folding position by a single rotating disk.

It will, of course, be understood that the 95 rotary carrier has in practice a web of paper delivered to it from a printing press or other mechanism, and that the web of paper is carried around the carrier by means of suitable pins, as 24, or other mechanism of any well-known and approved construction, but for purposes of clearness of illustration I have not shown the web of paper in the drawings, as the manner in which my improved folding mechanism acts upon it will be clearly understood by those skilled in the art.

What I claim as my invention and desire to secure by Letters Patent is:—

1. The combination with a rotary carrier, 100 a folding blade carried thereby, a cross head connected with said folding blade and provided with a recess at each end, and fold-completing mechanism, of a rotary member placed with its axis of rotation between the axis of rotation of said rotary carrier and the line of travel of said folding blade and rotating in the same direction as said rotary carrier, and an engaging stud on said rotary member adapted, while traveling in the same direction therewith, to engage said recessed 110 cross head while said cross head is in normal position, and, by its said engagement therewith and while traveling in the same direction, to operate said cross head and move said folding blade into folding position and 115 out of folding position into normal position.

2. The combination with a rotary carrier, 120 a folding blade carried thereby, a cross head connected with said folding blade and provided with a recess at each end, fold-complet- 125

ing mechanism, and a guide adapted to bear upon said cross head and hold the same in normal position when not being operated to fold the paper, of a rotary member placed 5 with its axis of rotation between the axis of rotation of said rotary carrier and the line of travel of said folding blade and rotating in the same direction as said rotary carrier, and an engaging stud on said rotary member 10 adapted, while traveling in the same direction therewith, to engage said recessed cross head while said cross head is in normal position, and, by its said engagement therewith and while traveling in the same direction, to 15 operate said cross head and move said folding blade into folding position and out of folding position into normal position.

3. The combination with a rotary carrier, a folding blade carried thereby, a cross head 20 connected with said folding blade and provided with a recess at each end, fold-completing mechanism, and a guide adapted to bear upon said cross head and hold the same in normal position when not being operated to 25 fold the paper, of a rotary member placed with its axis of rotation between the axis of rotation of said rotary carrier and the line of travel of said folding blade and rotating in the same direction as said rotary carrier, and 30 an engaging stud on said rotary member whose circle of travel intersects the circle of travel of said folding blade axis and adapted, while traveling in the same direction therewith, to engage said recessed cross head 35 while said cross head is in normal position, and, by its said engagement therewith and while traveling in the same direction, to operate said cross head and move said folding blade into folding position and out of folding 40 position into normal position.

4. The combination with a rotary carrier, a folding blade on said rotary carrier, a cross head on said folding blade provided with a recess at each end, and a guide adapted to 5 bear upon said cross head and hold the same in normal position while said folding blade is

not being operated, of a rotary member whose axis of rotation is between the axis of said rotary carrier and the line of travel of said cross head, means for driving said rotary member in the same direction with said rotary carrier and at a speed of four to three with relation thereto, three studs upon said rotary member equally distant from each other adapted, while traveling in the same 50 direction therewith, to engage said recessed cross head while said cross head is in normal position, and, by its said engagement therewith and while traveling in the same direction, to operate said cross head and move said folding blade into folding position and out of folding position into normal position.

5. The combination with a rotary carrier, a folding blade on said rotary carrier, a cross 60 head on said folding blade provided with a recess at each end, and a guide adapted to bear upon said cross head and hold the same in normal position while said folding blade is not being operated, of a rotary member 70 whose axis of rotation is between the axis of said rotary carrier and the line of travel of said cross head, means for driving said rotary member in the same direction with said rotary carrier and at a speed of four to three 75 with relation thereto, three studs upon said rotary member equally distant from each other whose circle of travel intersects the circle of travel of said folding blade axis and adapted, while traveling in the same direction therewith, to engage said recessed cross head while said cross head is in normal position, and, by its said engagement therewith and while traveling in the same direction, to operate said cross head and move said folding 80 blade into folding position and out of folding position into normal position.
